UNITED STATES PATENT OFFICE.

GEORGE THOMPSON, OF NEW YORK, N. Y.

DESIGN FOR A BOTTLE-CAP.

51,618.

Specification for Design.

Patented Dec. 18, 1917.

Application filed October 23, 1917. Serial No. 198,149. Term of patent 14 years.

To all whom it may concern:

Be it known that I, GEORGE THOMPSON, a subject of the King of Great Britain, and residing at the borough of Manhattan, in the city, county, and State of New York, have invented a new, original, and ornamental Design for Bottle-Caps, of which the following is a specification, reference being had to the accompanying drawing, forming part thereof.

Figure 1 is an elevation of a bottle cap, showing my new design, and

Fig. 2 is a plan view of the same.

I claim:

The ornamental design for a bottle cap, as shown.

GEORGE THOMPSON.
